Primary Examiner — Richard Kearney*Assistant Examiner* — David Weir(74) *Attorney, Agent, or Firm* — Dickinson Wright PLLC; Andrew D. Dorisio(57) **CLAIM**

The ornamental design for a conveyor module as shown and described.

DESCRIPTION

FIG. 1 is a top perspective view of the conveyor module showing our new design;

FIG. 2 is a bottom perspective view thereof;

FIG. 3 is a front view thereof;

FIG. 4 is a bottom view thereof; and,

FIG. 5 is a rear view thereof.

The broken lines in the figures depict portions of the conveyor module that form no part of the claimed design.
